UNITED STATES PATENT OFFICE

2,042,682

BAG

**Alfred F. Reilly, North Attleboro, Mass., assignor
to Evans Case Company, North Attleboro,
Mass., a corporation of Massachusetts**

Application September 26, 1935, Serial No. 42,326

7 Claims. (Cl. 150—29)

The invention relates to bags of the type in which there is a more or less rigid frame associated with the main body of the bag which may be of any suitable material. The frame members 5 may be of metal or of artificial compositions or of other materials. The main body of the bag may be of fabric, leather, mesh, chain or any other suitable material. The present invention has particularly to do with the method or means 10 for joining the main body of the bag to the frame members. Ordinarily the frame members are hinged together so as to provide means for access to the inside of the bag. The present invention 15 contemplates members to which the main body of the bag may be attached and which members themselves may be inserted into and removed from the frame members.

In order to clearly disclose the invention specific forms or embodiments thereof are illustrated 20 in the accompanying drawing of which Figure 1 is a side elevation of a bag constructed in accordance with the present invention portions being broken away to show underlying portions.

Fig. 2 is a plan view in expanded form of a 25 hinge connecting together the frame members.

Fig. 3 is a fragmentary side elevation from the inside of the bag of the lower end of the frame members associated with the hinge and with the member to which the main body of the bag may 30 be attached. Fig. 4 is a transverse vertical section on the line 4—4 of Fig. 3.

Fig. 5 is a fragmentary side elevation of one of the hinge members associated with one end of the member to which the main body of the bag 35 may be attached.

Figs. 6 and 7 are side elevations of two forms of members to which the main body of the bag may be attached.

The frame of the bag is illustrated as comprising two frame members 10 and 11 which may 40 be of any desired or usual form. They are here illustrated as U-shaped in cross section as more clearly indicated in Fig. 4 but this particular form is not essential. In general outline they are illustrated as forming three sides of a rectangle 45 although this form is not essential and they may be made in any of the forms suitable for bag frames and plain or ornamented. A catch 12 is diagrammatically illustrated for fastening and 50 releasing the frame members 10 and 11. At their lower ends the frame members at each side may be provided with a hinge structure 13. As illustrated in Fig. 2 the hinge structure is made of two members 14 and 15 fastened together by a 55 pintle 16a. The member 15 is formed with a

side wing 16 and on the member 14 is an oppositely disposed side wing 17 as illustrated in Fig. 2. While the wings 16 and 17 may be integral with the hinge members 15 and 14 this is not essential. As illustrated in Figs. 3 and 4 the hinge members 5 14 and 15 may be fastened by any suitable means such as welding, brazing, or soldering in the frame members 10 and 11 respectively so that the ends of the hinge members form lugs in the frame members. Before the hinge members are put in 10 place the wing members 16 and 17 will be bent upward at substantially right angles as indicated in full lines in Fig. 4.

In Fig. 6 is shown a member to which may be attached the main body of the bag. This bag 15 supporting member may consist of a suitably shaped wire or other like structure 18 shown as having at each end a flattened portion 19 provided on its outer edge with a hook 20 for a purpose hereinafter to be explained. As indicated 20 in Fig. 1 the main body of the bag 21 may be fastened to the member 18 by any suitable means. The bag body 21 may at its edge be wrapped around the member 18 and sewed thereto, or it may be sewed at its edge without turning over 25 or it may be attached in any other suitable manner. At the ends of the member 18 are provided holes 22 for convenience in rigidly fastening the bag body portion 21 at substantially the ends of 30 the usual side slits to hold the bag properly in place.

In Fig. 7 is shown another form of attaching member 18a which may be roughened or serrated in any suitable manner such as by twisting so as to provide seats for the thread or other bag 35 attaching means. While such a construction is not essential it may be desirable as an aid in maintaining the material of the bag body 21 in proper position.

The members 18 and 18a preferably will be 40 made of some resilient material or at least their ends 19 will be resilient. When the bag body 21 has been properly attached to the members 18 the members 18 will be inserted into the frame members 10 and 11. After they are inserted and 45 forced into place as illustrated in Fig. 1 the catches or hooks 20 will ride over the hinge members 14 and 15 and may engage and seat themselves upon lugs in the frame members which are shown as formed by the ends of the hinge members 50 14 and 15. By this means the bag will be held in place in the frame members 10 and 11 and will then be ready for use.

In order to assist in holding the catches 20 of the frame members in engagement with the hinge 55

members 14 and 15 the wing members 16 and 17 may be provided. When the bag carrying members 18 are inserted into the frame members 10 and 11 the wing members 16 and 17 will take the 5 position illustrated in Fig. 4 and on a larger scale in Fig. 5. After the hooks 20 have seated themselves on the ends of the hinge members 14 and 15 the ends of the wing members 16 and 17 may be bent over as illustrated in dotted lines in Fig. 4 10 bearing against the edges of the end portions 19 of the frames 18 forming tie members so as to tend to prevent the hooks 20 from withdrawing from the hinge members 14 and 15. If it should be desired to remove the body of the bag for any 15 purposes such as repairs or for substituting another bag body the ends of the wing members 16 and 17 may be bent back to the position illustrated in full lines in Fig. 4 and the resiliency or elasticity of the members 18 will allow the hooks 20 to be forced inward so as to release them from 20 the hinge members 14 and 15 when the members 18 carrying the bag body 21 may be withdrawn from the frame members 10 and 11.

While it may be preferable to employ some 25 such holding device as the wings 16 and 17 associated with the hinges 13 they are not essential and if desired may be omitted especially when the hooks 20 may be relied on to remain in contact or engagement with the hinge members 14 and 15.

30 The invention is not confined to the specific construction illustrated but may be embodied in other forms.

I claim as my invention:

1. A pair of frame members U shaped in cross 35 section, hinges connecting them together at their ends, lugs at the hinges, tie members at the lugs, supporting members for a bag corresponding in shape to the frame members and adapted to fit therein and having resilient ends, and catches on 40 the ends of the supporting members adapted to resiliently engage the lugs and to be held in place by the tie members.

2. A pair of hinged frame members, lugs on 45 the members, tie members at the lugs, supporting members for a bag corresponding in shape to the frame members and adapted to fit therein and having resilient ends, and catches on the ends

adapted to resiliently engage the lugs and to be held in place by the tie members.

3. A pair of frame members, hinges connecting them together at their ends, lugs at the hinges, supporting members for a bag corresponding in shape to the frame members and adapted to fit therein and having resilient ends, and outwardly extending catches on the ends of the supporting members adapted to resiliently engage the lugs laterally. 5

4. A pair of frame members U shaped in cross section, hinges connecting them together at their ends, supporting members for a bag corresponding in shape to the frame members and adapted to fit therein, catches on the supporting members, 15 lugs on the hinges adapted to be releasably engaged by the catches, and tie members at the lugs adapted to hold the catches in engagement with the lugs. 10

5. A pair of hinged members, supporting members for a bag corresponding in shape to the frame members and adapted to fit therein, catches on the supporting members, lugs on the hinged members adapted to be releasably engaged by the catches, and tie members at the 25 lugs adapted to hold the catches in engagement with the lugs.

6. A pair of frame members, hinges connecting them together at their ends, lugs at the hinges toward the outer sides of the frames, supporting 30 members for a bag corresponding in shape to the frame members and adapted to fit therein and having their ends resiliently biased outwardly, and catches on the outer sides of the ends of the supporting members adapted to resiliently 35 engage the lugs laterally.

7. A pair of frame members, hinges connecting them together at their ends, lugs at the hinges toward the outer sides of the frames, supporting members for a bag corresponding in shape to the 40 frame members and adapted to fit therein and having their ends resiliently biased outwardly, catches on the outer sides of the ends adapted to resiliently engage the lugs laterally, and tie members at the lugs adapted to hold the catches in 45 engagement with the lugs.

ALFRED F. REILLY.
